GRAB BUCKET

Herbert S. Atkinson, East Orange, N. J., assignor
to The Hayward Company, New York, N. Y., a
corporation of New York

Application June 6, 1938, Serial No. 212,006

11 Claims. (Cl. 37—186)

This application is a continuation in part of my prior application filed May 15, 1936, Serial No. 79,945. The invention relates to excavating, lifting or conveying apparatus and will be herein referred to as grab bucket apparatus, as a comprehensive term. The object is the practical operation of such grab bucket mechanism by means of hydraulic pressure generated in a pump carried by the bucket itself under control from a remote operator's station on a crane, or otherwise. Hydraulic grab buckets of such self-contained type offer many advantages in respect to capacity and power which have not heretofore been realized, because of the difficulties, among other things, in providing the proper reliable and continuous response to the remote control. By this invention the response is made as prompt and effective as in any mechanically controlled bucket and the advantages of the hydraulic type are thereby extended to the various uses to which it is adapted.

The invention is illustrated in its form at present preferred and somewhat schematically in the accompanying drawings, wherein Fig. 1 is an elevation of the bucket with parts in section;

Fig. 2 is a side elevation of Fig. 1, also with parts in section;

Fig. 3 is an enlarged longitudinal section of the automatic lock valve;

Fig. 4 is a section of Fig. 3;

Fig. 5 a section of the pressure reactor;

Fig. 6 a section of the pump;

Fig. 7 is an elevation partly in section of a modified form using a non-reversing motor, and

Fig. 8 an elevation partly in section at right angles to Fig. 7.

Referring first to Figs. 1 and 2 the bucket comprises a hydraulic cylinder 1 secured to or forming part of the head frame 2 and provided with a suspension eye 3, or equivalent means of attachment to a crane, boom, or other support, as will be understood. The bucket jaws 4, or equivalent grab members, are shown, in this case, as link-connected to the head frame 2 in a usual way and operated by the piston rod 5 of the cylinder 1. Raising the piston as by admission of pressure fluid to the low end of the power cylinder closes the jaw members together, or upon an object, and they remain closed so long as the pressure is maintained. On release of the pressure, or withdrawal from the cylinder of the pressure fluid, the jaws are opened and they may open by their own gravity, forcing the pressure fluid out of the cylinder.

The pressure fluid is desirably oil. A sufficient supply of it is contained in a reservoir 6 mounted on the head frame at one side of the upper part of the hydraulic cylinder, where it projects above the head frame. Oil from the lower part of the reservoir is pumped to the lower end of the cylinder by a pump 7 driven by an electric pump motor 8, both of which are secured to the under side of the head frame at one side of the lower part of the hydraulic cylinder. A gear-type pump is preferred because of its lower cost but other types would be suitable.

In the actual bucket the pipe connections of the hydraulic system, between the reservoir, power cylinder and pump are compactly housed in the head frame so as to be least liable to injury, but in the drawings, for purpose of description, they are shown spaced apart. When the jaw-mechanism is to be closed, the course of the oil is as follows: From the bottom of the reservoir 6 by pipe 9 and check valve 10 to the pump 7. The pump forces the oil by pipe 11 to the lock valve 12 and through the latter by line 13 to the lower end of the hydraulic cylinder and at the same time by line 14 to the pressure reactor 15.

This device, shown in larger scale in Fig. 5, is a cylinder secured to the underside of the head frame and containing a free piston 16 heavily loaded by a coil spring 17 and provided with a blow-off and pet cock 18 connected at a point above the piston stroke.

The lock valve 12, separately shown in Figs. 3 and 4 is mounted in an aperture in the head frame on the opposite side of the hydraulic cylinder from the oil reservoir 6, and comprises a piston-type slide valve 19 working in a valve-casing which is so ported that the pressure fluid has access to it on all sides, that is to say, the valve is balanced and thus the heavy pressures which it handles exert no tendency to bind it against the wall of its casing or interfere with the free and quick movement required of it. This valve member must have a specially close fit in its casing to avoid leakage and on this account, and notwithstanding its pressure balance, it requires considerably more power for its operation than can be practically obtained from solenoids or magnets as employed in usual forms of electro-magnetic valves. According to this invention it is operated by a rotary motor 20, through a winch-form chain connection 21 with its armature shaft. This motor is specially wound to produce a high torque and to be capable of sustaining a stalling over-load indefinitely with

out injury, which capacity is herein referred to by calling it a high-torque motor. Rotation of the armature shaft of this motor winds up the chain to pull the valve to its open position 5 against the spring 22, and ceases when the valve reaches the limit of its stroke. It will hold it indefinitely in this position. When the motor is de-energized the spring 22 is strong enough to snap the valve instantly back to its closed position. Proper response action requires that this valve have a short stroke and liberal portway so as to be quick in its change from full open to full closed position. It is pointed out that due to the mounting of the power cylinder directly 10 on the head frame the whole liquid part of the system is rigid and devoid of packing glands which, under the conditions of use of this type of apparatus, are practically impossible to keep tight against leakage.

20 In the form of the invention shown by Figs. 1 and 2, the pump motor 8 is of the reversible type, and the bucket jaws are closed by driving the pump in one direction, to force fluid into the cylinder and opened by driving it in the opposite direction to withdraw the fluid. The circuit of the lock valve is connected with that of the pump motor so that it is open whenever the motor is driving the pump in either direction but closes instantly when it stops.

30 In the reversed drive, to open the jaws, the pump withdraws the pressure fluid from the power cylinder through the same pipe connections by which it entered, but by virtue of the check valve 10 the fluid is returned to the reservoir by the check-valved by-pass 22, which opens into the top of the reservoir, or above the liquid level therein. This method of return is a factor of great importance in preserving a constant response relation between the hydraulic and electric sides of the system, because it affords an opportunity for air to escape from the oil and avoids foaming under long-sustained bucket operation with its frequent flow reversals. By causing the oil to flow always in one direction through 40 the reservoir and by the use of screening over the outlet, air entrainment is avoided.

45 The reservoir is vented to atmosphere at its top by a vent 25.

50 The electrical connections 23 to the pump motor and electric lock valve extend in the form of a flexible cable to the controller 24 (Fig. 1), which will be understood to be located at the operator's station on the crane or elsewhere, and connected to a source of current supply. It will be understood from Fig. 2 that two of the four 55 circuit wires 23 lead to the field coil and two to the armature of the pump motor and that the lock-valve motor is in parallel across the latter so that, in this form, the lock-valve opens instantly on the starting of the pump and closes 60 instantly on its cessation.

65 In the hydraulic system used in Figs. 7 and 8, the pump motor, here marked 26 is uni-directional in operation and the pipe system and lock-valve are organized somewhat differently as follows: The pump 7 delivers pressure fluid through a check valve 27 to the pipe line 13 to the power cylinder. The balanced valve 12, which is the same as above described, is connected in a separate return branch pipe line 28 leading from the power cylinder direct to the top of the reservoir, and is closed when the pump operates. When the bucket jaws are closed together or upon an object, the pressure fluid is thus positively confined as before in the cylinder, by the

check valve 27 in the delivery line and by the electro-magnetic valve 12 in the return line.

When the jaws are to be opened, the lock valve 12 is opened and the weight of the jaws suffices to force the pressure fluid back through the valve 5 12 and pipe 28 to the reservoir 6, the flow through the reservoir being in one direction, as before. For the control of this bucket, the lock valve motor 20 has its separate circuit, independent of the pump motor circuit, direct to the controller 10 29 at the operator's station. Though separately shown, both circuits may be included in a single cable as will be understood.

20 In the controller, the contacts will be understood to be so organized that when the handle 15 is thrown in one direction it causes the pump to be driven and the lock-valve to be closed thereby closing the jaws and, when moved a certain distance in the opposite direction, stops the current to the pump motor, to hold the jaws closed and then, when moved to a further stop, opens the lock-valve. This lets the jaws swing open by their gravity. The detail of the controller contacts is not shown because such apparatus is well understood in the electrical art.

25 In both of the illustrated forms of the invention, on each closing of the jaw mechanism, the pump delivers somewhat more oil than actually enters the power cylinder. The excess passes 30 into or toward the reactor cylinder above described and more or less compresses the heavy spring therein. At some point in its compression the pressure in the oil may become increased to such degree as to open a spring-loaded by-pass 35 (Fig. 6) built into the pump structure, and discharge any further delivery of oil through this by-pass back to the suction side of the pump. The spring acting on the by-pass valve serves 40 as a resilient means for limiting the pressure which the pump can develop in the power cylinder. It is set so that it yields only after the piston of the pressure reactor 15 has been somewhat displaced against its spring and the latter, supplemented to some slight extent by the air 45 confined in the cylinder above the piston, has been put under compression. When the pressure fluid has been locked in the power cylinder, as above described, the reaction of this spring thereon continues and sustains the pressure and keeps the jaws closed when the pump has stopped. The 50 function of the pressure reactor can be performed by other analogous mechanism but, as here shown, is made as a cylinder of such capacity as to provide a continuing pressure for an indefinite time notwithstanding the possibility of 55 leakage at the piston rod packing, which may develop with wear. At the same time the pressure reactor serves as a cushion which levels off the pressure surges incident to the abrupt stopping and reversals of the oil flow, thus eliminating 60 injurious vibration and reducing the wear as well as the noise of operation.

65 While two forms of the invention have been illustrated, by way of exemplification, it is to be understood and will be apparent that other forms 65 are also possible within the scope of the claims which follow.

I claim:

1. In a hydraulically operated grab bucket of the kind in which the hydraulic system including 70 reservoir, electric pump and power cylinder are all incorporated in the bucket structure and remotely controlled through flexible leads, the improvement which comprises the combination with such system of a pressure reactor subject to the 75

pressure developed by the pump and reacting to close the bucket when the pump stops.

2. In a hydraulically operated grab bucket of the kind in which the hydraulic system including reservoir, electric pump and power cylinder are all incorporated in the bucket structure and remotely controlled through flexible leads, the improvement which comprises in such system a spring-loaded by-pass for the pumped fluid and a pressure reactor subject to the pump-developed pressure and including a reactor spring adapted to yield to a lower pressure than said by-pass spring.

3. In a hydraulically operated grab bucket of the kind in which the hydraulic system including reservoir, electric pump and power cylinder are all incorporated in the bucket structure and remotely controlled through flexible leads, the improvement which comprises the combination with such system of a spring-loaded by-pass for the pumped fluid, a pressure reactor for keeping the bucket closed and locking means for maintaining the pressure on said reactor when the motor stops.

4. In a hydraulically operated grab bucket of the kind in which the hydraulic system including reservoir, electric pump and power cylinder are all incorporated in the bucket structure and remotely controlled through flexible leads, the improvement which comprises in such system, a pressure reactor and an electro-magnetic lock-valve of the kind consisting of a piston-type, pressure-balanced valve member provided with a high-torque rotary motor energized coincidently with the pump motor to open said valve.

5. In a hydraulically operated grab bucket of the kind in which the hydraulic system including reservoir, electric pump and power cylinder are all incorporated in the bucket structure and remotely controlled through flexible leads, the improvement which comprises the combination in such system of a pressure reactor subject to displacement by the pumped fluid and an electro-magnetically controlled lock-valve for locking the pressure on said reactor.

6. In a hydraulically operated grab bucket of the kind in which the hydraulic system including reservoir, electric pump and power cylinder are all incorporated in the bucket structure and remotely controlled through flexible leads, the improvement which comprises the combination in such system of a lock-valve to prevent return flow from the cylinder toward the reservoir and a pressure reactor comprising a cylinder containing a spring-pressed piston connected to the circuit between the cylinder and said valve.

7. In a hydraulically operated grab bucket of the kind in which the hydraulic system including reservoir, electric pump and power cylinder

are all incorporated in the bucket structure and remotely controlled through flexible leads, the improvement which consists in said reservoir having separate inlet and outlet pipes, the outlet pipe extending from the bottom and the inlet entering at a point remote from the outlet and a lock-valve connected for preventing fluid flow from the cylinder to or through said inlet.

8. In a hydraulically operated grab bucket of the kind in which the hydraulic system including reservoir, electric pump and power cylinder are all incorporated in the bucket structure and remotely controlled through flexible leads, the improvement which consists in said reservoir having separate inlet and outlet pipes, the outlet pipe extending from the bottom and the inlet entering from a point remote from the outlet, a lock-valve connected to prevent fluid flow from the cylinder through said inlet and a pressure reactor cylinder connected to the system on the cylinder side of said lock-valve.

9. In a hydraulically operated grab bucket of the kind in which the hydraulic system including reservoir, electric pump and power cylinder are all incorporated in the bucket structure and remotely controlled through flexible leads, the improvement which comprises the mounting of said power cylinder rigidly on the bucket head frame with its piston connected to the jaw mechanism, the pipe connections between said cylinder and pump thus constituting a rigid system and including an electro-magnetic lock-valve to confine the cylinder pressure and a pressure reactor acting to close the bucket.

10. In a hydraulically operated grab bucket of the kind in which the hydraulic system including reservoir, electric pump and power cylinder are all incorporated in the bucket structure and remotely controlled through flexible leads, the improvement which consists in said pump being a reversible pump and said reservoir having separate inlet and outlet pipes with respectively oppositely directed check-valves therein, connecting it with said pump and an electro-magnetically operated lock-valve between the cylinder and said inlet pipe.

11. In a hydraulically operated grab bucket of the kind in which the hydraulic system including reservoir, electric pump and power cylinder are all incorporated in the bucket structure and remotely controlled through flexible leads, the improvement which consists in said pump being non-reversing and having a check-valved connection to the power cylinder and said reservoir having a return connection from the cylinder around the pump and a lock-valve in the latter connection.

HERBERT S. ATKINSON.
